UNITED STATES PATENT OFFICE.

ROBERT MUNN DIXON, OF EAST ORANGE, NEW JERSEY, ASSIGNOR TO THE SAFETY CAR HEATING AND LIGHTING COMPANY, OF NEW YORK.

DESIGN FOR A GAS-RECEIVER.

SPECIFICATION forming part of Design No. 29,174, dated August 9, 1898.

Application filed June 10, 1896. Serial No. 595,032. Term of patent 3½ years.

To all whom it may concern:

Be it known that I, ROBERT MUNN DIXON, of East Orange, county of Essex, State of New Jersey, have produced a new and original Design for Gas-Holders or Gas- Receivers, of which the following is a specification, reference being had to the accompanying drawings.

The object of my invention is to produce an improved design for gas cylinders, holders, or receivers especially adapted for transporting gas under pressure, as is usual in railway-car service or the like.

Figure I is a side elevation of a receiver, showing my design. Fig. II is an end view thereof. Fig. III is a central vertical section of one end thereof.

The leading feature of my design consists in a cylindrical body part provided at opposite ends, respectively, with a curved head formed of a section of a sphere and united to the body part by overlapping annular-curved edges on the body part.

Referring to the figures on the drawings, 1 indicates a cylindrical body part of my holder, and 2 each of the heads thereof with which it is provided at its opposite ends. Each head is made of a section of a sphere and fits within the end of the cylinder 1, the cylinder being provided with an overlapping curved edge or flange 3 for the reception of the head. Upon its inner side the head is provided with a thickened reinforcement or boss 5.

What I claim is—

The design for a gas cylinder, holder, or receiver, substantially as herein shown and described.

In testimony of all which I have hereunto subscribed my name.

ROBERT MUNN DIXON.
